(57) **CLAIM**

The ornamental design for a bottle, as shown and described.

DESCRIPTION

FIG. 1 is a front elevational view of a bottle showing my new design, the rear elevational view being a mirror image thereof.

FIG. 2 is a top plan view thereof.

FIG. 3 is a left side elevational view thereof, the right side view being a mirror image thereof.

FIG. 4 is a top perspective view thereof; and,

FIG. 5 is another top perspective view, with the flexible top in a folded position.
